GAME BOARD

Ernest F. C. Salmon, North Hollywood, Calif.

Application February 5, 1954, Serial No. 28,876

Term of patent 14 years

(Cl. D34—5)

To all whom it may concern:

Be it known that I, Ernest F. C. Salmon, a subject of the Queen of Great Britain, residing at North Hollywood, in the county of Los Angeles and State of California, have invented a new, original, and ornamental Design for a Game Board, of which the following is a specification, reference being had to the accompanying drawing, forming part thereof.

The drawing is shaded to illustrate contrast of color.

This application is a continuation-in-part of my application Serial No. D. 18,666, filed February 26, 1952, now abandoned.

I claim:

The ornamental design for a game board, as shown and described.
